UNITED STATES PATENT OFFICE

JOSEF MARIAN, OF VIENNA, AUSTRIA

BOTTLE CAPPING MACHINE

Application filed March 19, 1931, Serial No. 523,810, and in Austria March 18, 1930.

This invention relates to bottle capping machines.

Among the important objects of the invention are to provide an improved general construction of machine for this purpose; to provide a capping machine wherein a die is used for forcing the cap down on the bottle and cheeks or jaws are used to crimp the cap into a groove in the bottle neck, the mechanism used being of improved and novel construction; to provide a machine of this class having a novel arrangement of neck engaging clamps for holding the bottle during the capping operation proper; and to provide operating means arranged by a single movement to successively actuate the neck clamps, the die and the cap crimping cheeks in the order named.

One form of the device for the carrying out of the process according to the invention, and three forms of cap for use in conjunction therewith, are shown, by way of example, in the accompanying drawings, in which

Figs. 1 and 2 show the said device before the beginning of the closing movement, in vertical section and plan elevation respectively,

Figs. 3 to 8 represent details of the device in elevation,

Figs. 9 and 10 show the device at the termination of the closing movement, in vertical section and side elevation respectively,

Figs. 11 and 12 show a detail of the device, in side elevation and plan view respectively, and

Figs. 13 to 15 show three forms of the closing cap, in section.

Referring to Fig. 1 the neck 1 of the bottle is provided with two external grooves 2, 3, and with a shoulder 4 on the inner surface of its orifice. This shoulder is adapted to receive and support the packing 5 of the cap 6, when the latter is placed over the mouth of the bottle.

The cramping tool comprises a casing 7 the lid 8 of which has a central aperture 9 to receive the neck of the bottle. The upper constricted portion of this casing is provided internally with steep-pitch threading 10 with

which a screw-disc 11 (Figs. 11 and 12), serving as a pressing die, is adapted to engage. This disc is provided with concentric slots 12 to receive pins 13 attached to the under surface of a plate 14. The screw-disc 11 is pressed against the plate 14 by a spring 15 inserted between a collar on the plate 14 and the head of a bolt 16 screwed into the disc 11. 55

With the plate 14 there is connected a cap 17 which embraces the upper portion of the casing 7, and also an arm 18 which, together with an arm 19 attached to the casing 7, forms the handles for the operation of the device, to be moved in the manner of the handles of a pair of pliers. 60

In the lower portion of the casing 7 there are located in superposition four rings 20-23 of which the two outermost (20, 23) are fixed, while the remaining two (21, 22) are rotatably mounted. As shown in Figs. 3, 5, 6, and 8 (on a reduced scale) the rings 20 and 23 are provided with radial slots 24, 25, the ring 21 with tangential slots 26, and the ring 22 with angular slots 27 each formed of a tangential and a concentric portion. Between the rings 20 and 21 there are arranged four ring segments 28 (see Fig. 4) which serve for the clamping of the device on to the neck of the bottle. Each of these segments is provided on both sides with pins 29 which engage in the slots 24, 26 of the discs 20, 21. Between the rings 22 and 23 there are arranged eight segments (see Fig. 7) adapted to act as cramping cheeks, in two layers of four each, of which the lower are denoted by 30 and the upper by 31. Each segment is provided on both sides with pins 32 which engage in the slots 27, 25 in the rings 22, 23. 75

The ring 21 is provided with an extension 33 projecting from the casing 7, to which extension there is attached an angle-piece 34 which is connected with the arm 18 by means of a tensile spring 35. The ring 22 is likewise provided with an extension 36 to which a frame 37 is attached through which the arm 18 projects. The arms 18 and 19 are pressed apart by means of a spring 38. 90

The mode of operation of the device is as follows:—

After the placing of a closing cap 6 with 100

its packing upon the mouth of the bottle to be sealed, and after the fitting of the device over the same, the arms 18 and 19 are pressed together. It is possible to effect this with 5 one hand, since an angle of movement of about 26° is sufficient for the present purpose. The work of cramping on the cap is effected, during the pressing together of the arms 18 and 19, in the following three stages:—

10 1. The arm 18 moves with it the angle-piece 34, through the intermediary of the spring 35, so that the ring 21 is turned in the casing. The segments 28 are thereby compelled to move radially inwards so as to 15 engage in the groove 2 in the neck of the bottle, and thus to clamp the device in position on the bottle. The length of the slots 12 in the screw-disc 11 are so proportioned that the pins 13 travel idly in these slots during this first stage.

20 2. On the further movement of the arm 18 the pins 13 carry the screw-disc forward with them compelling the same to move downwards in the screw-threading 10, so that the 25 closing cap is pressed down, and its packing compressed to a thickness of about 4 mm. The plate 14 participates in the downward movement of the screw-disc under the influence of the spring 15 until the same is 30 checked, e. g. until the rim of the cap 17 meets the shouldered-out surface of the casing 7. On the further rotation of the plate the pins 13 must withdraw from the slots 12.

35 3. The lever 18 now comes in contact with the frame 37, and effects the rotation of the disc 22, whereby the cheeks 30, 31 are moved inwards, so that the wall of the closing cap is pressed into the groove 3 in the bottle-neck.

40 The device has now attained the position in which it is shown in Figs. 9 and 10. On the releasing of the arms 18, 19 these same are pressed apart by the spring 38, and the screw-disc 11 is lifted by the spring 15.

45 The cap 17 is provided, as shown in Fig. 10, with slots 39 in which pins 40 attached to the outside of the casing engage. There are thus provided retaining means for the cap 17 and the plate 14 connected therewith, so that these parts cannot be lifted by the reaction to the 50 pressure exerted on the screw-disc 11 during the second stage of the cramping process. It is also possible to employ, in place of the screw-disc 11, a merely axially guided pressing die the downward movement of which 55 is effected by the oblique portion of the slots 39.

60 It will be clear from the above description that the device can be constructed as a hand tool, so that the present invention enables even the smallest businesses, which are not 65 in a position to install expensive sealing plant, to effect the tight sealing of their products in a manner which is both simple and inexpensive. The device can, however, also be 70 driven by machinery. As compared with the

known capsule stoppers the new cap provides the further advantage of great saving of material, since the capsule stoppers require, for a completely tight seal, a cork of 2-3 cm. in length, while for the present type of cap a cork of 1 cm. in length is sufficient to obtain a perfect seal.

75 Figs. 13 and 14 show caps suitable for the carrying out of the present purpose. In the form shown in Fig. 13 the head of the cap is provided with an annular inwardly projecting fold 41 by means of which the packing 5 is retained in position in the cap before use.

80 In the form of cap shown in Fig. 14 the side wall is returned inwardly and its edge 42 is returned again in an axial direction so as to form a ring-shaped rib for holding the packing 5 in position.

85 The packing can also be attached to the inside of the cap in any other desired or suitable manner, for example by means of an adhesive.

90 Referring to Fig. 15, the head 43 of the cap 6 is provided with an annular depression 44, being curved upwards. The disc 11 has a projection 45 on its undersurface, acting upon the curved portion of the head and pressing the edge 46 of the depression 44 into the groove on the inside of the neck 1 while flattening the said curved portion of the 95 head 43.

What I claim is:

1. A device for sealing bottles or the like by means of caps, comprising a casing adapted to be fitted over the mouth of a bottle, a die mounted in the upper part of the casing and movable axially thereof, a cap clamping cheeks mounted in the lower part of said casing and guided for rectilinear radial movement with respect to the axis of 100 said casing, means for actuating said die and cheeks, and means carried by the casing for clamping the latter on the neck of a bottle.

105 2. A device according to claim 1 wherein the last mentioned means consists of a second set of radially movable clamping cheeks within the lower part of the casing.

110 3. A device for sealing bottles or the like by means of caps, comprising a casing adapted to be fitted over the mouth of a bottle, a die mounted in the upper part of the casing and movable axially thereof, cap clamping cheeks mounted in the lower part of 115 said casing and guided for rectilinear radial movement with respect to the axis of said casing, means carried by the casing for clamping the latter on the neck of a bottle, and operating means arranged to operate the last means, the die and the cheeks successively 120 in the order named.

125 4. A device according to claim 1 wherein the die and casing have screw threaded engagement and means are provided to rotate the die and thereby cause it to move axially 130 of the casing.

5. A device according to claim 1 wherein the die and casing have screw threaded engagement and the die is provided with concentric slots in its upper surface and means are provided to rotate the die consisting of
5 a plate rotatably mounted in the casing above the die, studs on the plate engageable in the slots of the die, and an operating member attached to said plate.
6. A device according to claim 1 wherein
10 the die and casing have screw threaded engagement and the die is provided with concentric slots in its upper surface and means are provided to rotate the die consisting of
15 a plate rotatably mounted in the casing above the die, studs on the plate engageable in the slots of the die, an operating member attached to said plate, and means carried by the plate and casing for effecting camming of the plate toward the die upon the plate being rotated to effect pressing movement of said die.
7. A device for sealing bottles or the like by means of caps, comprising a casing adapted to be fitted over the mouth of a bottle,
25 a die mounted in the upper part of the casing and movable axially thereof, cap clamping cheeks mounted in the lower part of said casing and guided for rectilinear radial movement with respect to the axis of said casing, a second set of radially movable clamping cheeks within the lower end of the casing and below the first set to engage the bottle neck below the cap, rings fixed within the casing
30 above and below said cheeks and provided with radial slots, studs on said cheeks engaging in the slots of said rings and means for moving said cheeks inwardly and outwardly.
- 35 8. A device according to claim 7 wherein the last means consists of a pair of rotatable rings each having eccentric slots receiving the studs of a respective cheek, and means for rotating the last mentioned rings.
- 40 9. A device according to claim 7 wherein the last means consists of a pair of rotatable rings each having eccentric slots receiving the studs of a respective cheek, and means for rotating the last mentioned rings, said last means being operatively connected to the means for actuating the die in such manner that the last mentioned cheeks engage the bottle neck, the die is actuated to clamp a cap and the first mentioned cheeks effect crimping of the cap in the order named.

In witness whereof I have signed this specification.

JOSEF MARIAN.
